HAIRDRESSING ACCESSORY

John A. Sewol, Hempstead, N. Y.

Application June 12, 1946, Serial No. 676,139

7 Claims. (Cl. 132—1)

1

The present invention relates to devices pertaining to the art of hairdressing and more particularly concerns devices for holding, mounting and using hairpins, especially of the type known as "bobby" pins.

The most commonly used form of hairpin today is the type known as the "bobby" pin, which consists of a U-shaped piece of flat spring steel having the legs of the U close to one another. One or both legs may be corrugated to maintain the pin more securely in the hair. Because of the springiness and the close contact of the legs of the pin, difficulty is often encountered in opening the pin for insertion in the hair despite the usual provision of a slight flaring of the ends of the pin legs. Ordinarily, it requires both hands to open the pin, one for holding the pin and the other for spreading its legs. Otherwise, if only one hand is free for use, recourse must be had to other means, such as the teeth, to assist in spreading the pin. This is an unsightly practice as well as an awkward one.

According to the present invention, these difficulties are overcome by the use of an accessory device which is simple to use, and provides a ready means of spreading such pins and can furthermore be used as a holder for such hairpins to keep them in readiness for instant use. Such an accessory is highly useful to persons such as hairdressers who use many such pins daily and customarily have only one free hand, the other hand being engaged in holding the hair into which the hairpin is to be inserted. However, it is also very useful to the ordinary lady-in-the-street, to assist her in conveniently carrying these pins in readiness for instant use, either in her handbag or upon her dressing table.

Other objects and advantages of the present invention will become apparent from the following specification and the accompanying drawings, in which

Fig. 1 is a perspective view of a preferred form of the invention;

Fig. 2 is an end elevation view of the device of Fig. 1, showing its relation to the hairpin after mounting;

Fig. 3 is a rear perspective view of another form of the present invention, useful as a hairpin stand or mount;

Fig. 4 is an end elevation view of a modified form of the device of Figs. 1 and 2, adapted for simpler fabrication; and

Fig. 5 is an end elevation view of a simplified version of the device of Fig. 3.

Referring to the drawings, Fig. 1 is a perspective

view of a preferred embodiment of the invention, which comprises an integral element 10 especially formed to provide the advantages of the present invention. Fig. 2 is an end elevation view of the same element showing its relation to a "bobby" pin 11, when mounted thereon. The pin holder and spreader of the present invention is preferably rectangular in plan view and has a thin flat portion 13, which is thin enough to be inserted between the slightly flaring tips of the conventional pin of this type. Joined to the flat portion 13 is a wedge-shaped portion 14, which is here illustrated as triangular in cross section although many other shapes may be used so long as that portion 14 is provided with a wedge surface 16 forming an obtuse angle with the surface of flat portion 13, this angle being preferably between 120° and 150°. Wedge surface 16 is preferably provided with a series of parallel grooves 17 extending perpendicular to the front edge 18 of flat portion 13, and each adapted to receive one pin.

In use, the pin is placed with its open end adjacent front edge 18. When holding the pin in the natural manner, with the thumb and fore finger on either side, touching both legs of the pin, the pin may be slid easily over flat portion 13 of the holder-spreader 10, perpendicular to edge 18. The flat portion 13 easily enters between the legs of the pin, since its slight thickness hardly spreads the pin. When the wedge surface 16 is reached, the pin is guided to enter one of the slots 17. Continued movement of the pin forces its legs to spread, so that the fingers can now naturally hold one leg while simultaneously preventing the other leg from approaching the first leg. The pin is now in proper condition and in perfect position in the fingers, to be inserted in the hair. In this way, the device serves as a convenient pin-spreader.

Instead of merely using the present device as a pin-spreader, it may be used as a holder. By forcing the pin up the slope of wedge surface 16 until the first corrugation in the upper pin leg passes over the top edge 19 of wedge surface 16, the pin will be retained in that position by its inherent springiness, and many pins may be thus mounted parallel to one another, each in its own groove, and easily carried about, in a lady's handbag for instance. Thus, the pins are carried mounted in readiness for instant use. Normally, for portable use, a cover with a snap fastener would be placed around the holder and its mounted pins, to prevent accidental dislodgment.

It will be understood that the flat portion 13 may also be provided with grooves similar to

grooves 17 for maintaining convenient spacing between the mounted pins, so as to facilitate individual removal.

As a modification of the portable form of the invention, shown in Figs. 1 and 2, it may be incorporated into a stand, as shown in Fig. 3, suitable for keeping conveniently upon a lady's dressing table or upon a hairdresser's table. For this purpose, a flat support portion 21 is provided, sufficiently long to give stable equilibrium. The flat portion 13' then extends upward at a convenient angle, while the wedge surface 16' may be substantially horizontal, and bears grooves 17' as in Fig. 1. Similar grooves 22 are formed in at least that part of flat portion 13' nearest front edge 18'. Grooves 22 may be extended for the full depth of flat portion 13', if desired. It will be understood that similar grooves may also be provided for the form of Fig. 1.

The devices of Figs. 1 and 3 are preferably integrally formed from a single solid piece of suitable material, such as a synthetic thermoplastic or thermo-setting material, as by molding, casting or machining. However, other materials may be used, where adaptable. Figs. 4 and 5 show forms of the device similar to Figs. 1 and 3, respectively, and fabricated from a blank of sheet material, such as cardboard or heavy stiff paper, or other similar stiff material, instead of as a solid piece. The blank is scored in conventional manner and is then bent as indicated in Figs. 4 and 5. The folds lying flat against one another are suitably fastened together, as by gluing or stapling or otherwise, resulting in a rigid, light and inexpensive structure. Parallel grooves, similar to 17 and 17', may be embossed or impressed into the sheet material before folding to provide guides for the hairpins, as described above.

While the invention has been illustrated in concrete form in a few embodiments thereof, it will be apparent that many equivalent structures can be devised, and the scope of the invention is not limited merely to the forms shown, but as defined by the appended claims.

I claim:

1. A hairpin spreading and holding device having a thin flat portion and a wedge surface portion, both adapted to be inserted between the legs of a pin to spread them apart and maintain them in spread condition ready for use.
2. A device as in claim 1 wherein said wedge surface portion is formed with a plurality of parallel grooves each adapted to receive a pin.

whereby a plurality of pins may be mounted in spaced parallel relation.

3. A device as in claim 1 further including a support portion formed integrally with said flat and wedge portions for serving as a support for permitting use of said device as a hairpin stand.

4. A hairpin spreading and holding device having a thin flat portion and a further portion adjoining said flat portion, said further portion having a wedge surface inclined at an obtuse angle to said flat portion, the front edge of said flat portion being separated from the upper edge of said wedge portion by a distance smaller than the length of the pin to be held thereby, whereby said thin flat portion is adapted to be inserted between the legs of said pin so that upon further relative movement between said pin and said device, the legs of said pin are spread by said wedge surface.

5. A device as in claim 4, wherein at least part of said flat portion is formed with spaced parallel grooves extending substantially perpendicularly to said front edge and each adapted to receive a pin to be mounted, whereby a plurality of pins may be mounted on said device in spaced parallel relation.

6. As an article of manufacture, a hairpin mount formed of a folded flat sheet and having a pair of adjacent parallel folds forming a thin portion, and a third fold disposed at an obtuse angle to said pair of folds.

7. An article of manufacture according to claim 6, wherein said sheet is formed with parallel spaced grooves, along one of said parallel folds and along said third fold, to provide guides for mounting hairpins thereon.

JOHN A. SEWOL.
